[57] CLAIM

The ornamental design for a backpack grocery carrier, as shown and described.

DESCRIPTION

FIG. 1 is a side elevational view of my backpack grocery carrier showing my new design.

FIG. 2 is a rear elevation view thereof.

FIG. 3 is a front elevation view thereof.

FIG. 4 is a top plan view thereof.

FIG. 5 is a front perspective view thereof.

The side of the grocery carrier not shown is a mirror image of the side shown.

Fig. 3

Fig. 4
